Primary Examiner — John Windmuller*Assistant Examiner* — John R Yeh(74) *Attorney, Agent, or Firm* — WPAT, P.C., Intellectual Property Attorneys; Anthony King(57) **CLAIM**

The ornamental design for a toy robotic arm, as shown and described.

DESCRIPTION

FIG. 1 is a perspective view of a toy robotic arm showing my new design;

FIG. 2 is another perspective view thereof;

FIG. 3 is still another perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines represent portions of the toy robotic arm that form no part of the claimed design.

1 Claim, 9 Drawing Sheets(56)
